UNITED STATES PATENT OFFICE

PAUL F. LEWIS, OF PITTSBURGH, PENNSYLVANIA, ASSIGNOR TO E. I. DU PONT DE NEMOURS & COMPANY, OF WILMINGTON, DELAWARE, A CORPORATION OF DELAWARE

REEL

Application filed July 27, 1928. Serial No. 295,687.

This invention relates to reels and more particularly to a reel in which the web, or body member, on which the material is to be wound is adapted to holding an object.

5 In devices of this general nature heretofore known and used, the body member has been adapted to support the flange members and have the material wound about it but, so far as we know, in none has the body 10 member been designed to serve these purposes and in addition act as a container.

An object of this invention is to provide a reel in which the body member is a container; a further object is to provide a reel 15 of simple construction in which the body member will act as a container for percussion caps and around which the lead-in wires may be wound. Other objects will appear hereinafter.

20 These objects are accomplished by the following invention of a reel so designed that the body member will serve as a container.

Referring more particularly to the drawings, Figure 1 is a sectional view of one 25 embodiment of the invention. Figure 2 is a sectional view taken along the line 2—2 of Figure 1 looking in the direction of the arrows and Figure 3 is a view in perspective.

The flange, or end members, 1 are preferably circular in form and are attached to the web, or body member, 2. The body member 2 is preferably formed of a single continuous strip so formed as to provide pockets or containers 3 into which percussion caps or like objects may be placed. The reel may be constructed of cardboard, wood, sheet metal, or the like. When the reel is used for percussion caps, the cap 4, itself, is slipped into the pocket 3, as shown in Figure 2, and 40 the lead-in wires 5 wound around the body member 2. The ends of the lead-in wires 5 may be carried through the notch 6 and passed into the opening 7. If desired, a percussion cap may be placed in each of the containers 3 and both sets of lead-in wires 5 wound around the body member 2, or the body member 2 may be so constructed as to accommodate an even greater number of percussion caps or like objects.

50 As many apparently widely different em-

bodiments of this invention may be made without departing from the spirit and scope thereof, it is to be understood that I do not limit myself to the specific embodiments thereof except as defined in the appended 55 claims.

I claim:

1. As an article of manufacture a reel comprising flange members and a multiplicity of containers interposed in a plane between 60 and parallel with the flange members and serving as attachment means for the flange members.

2. As an article of manufacture a reel comprising flange members and a multiplicity of 65 containers formed from a single strip of sheet material interposed in a plane between and parallel with the flange members.

3. As an article of manufacture a reel comprising flange members and a multiplicity of 70 containers interposed in a plane between and parallel with the flange members, said containers being adapted for the reception at either end of the article to be contained 75 therein.

In testimony whereof I affix my signature.
PAUL F. LEWIS.
